DESIGN FOR A SET OF GAME PIECES

Ammiel F. Decker, Pelham, N. Y.

Application July 24, 1933. Serial No. 48,813

Term of patent 14 years

To all whom it may concern:

Be it known that I, AMMIEL F. DECKER, a citizen of the United States of America, residing at 142 Monterey Avenue, Pelham, in the county of Westchester and State of New York, have invented a new, original, and ornamental Design for a Set of Game Pieces, of which the following is a specification, reference being had to the accompanying drawing, forming part thereof.

I claim:

The ornamental design for a set of game pieces as shown.

AMMIEL F. DECKER.
